UNITED STATES PATENT OFFICE.

EVA MAYNARD MARTIN, OF MEADVILLE, PENNSYLVANIA, ASSIGNOR TO THE SPIRELLA COMPANY, A CORPORATION OF PENNSYLVANIA.

ABDOMINAL GIRDLE.

1,082,204.

Specification of Letters Patent. Patented Dec. 23, 1913.

Application filed January 2, 1912. Serial No. 669,094.

To all whom it may concern:

Be it known that I, EVA MAYNARD MARTIN, a resident of Meadville, in the county of Crawford and State of Pennsylvania, have invented a new and useful Improvement in Abdominal Girdles, of which the following is a specification.

This invention relates to abdominal girdles, supports or bandages.

10 The object of the invention is to produce a construction of the character described which provides firm support for all parts of the abdomen at all times and is simple in construction and effective in use.

15 The invention comprises the construction and arrangement of parts hereinafter described and claimed.

In the drawings Figure 1 illustrates the application of an abdominal girdle constructed in accordance with my invention, and as the same appears when in position on the wearer; Fig. 2 is a plan view of the front half of the girdle as if the same were opened and spread out upon a flat surface; 25 Fig. 3 is a similar view of the rear half of the girdle, and Fig. 4 is a view of a stay or rib.

It has been customary in the construction of prior abdominal girdles to attach the garter supports to or at the lower edge of the girdle. In use of such devices, it is found that the strain upon the garter supports causes the girdle to bulge or gap outwardly from the body at its lower portion, with the result of giving little or no support to the lower portion of the abdomen.

My invention is designed to remedy the objectionable features of prior devices and to furnish continuous support to the abdomen at all points.

My improved girdle or bandage is formed of a front half or section 1 and a rear half or section 2, respectively provided with rows of eyelets 3, 3^a for fastening them together and securing the girdle about the body of the wearer. I prefer to divide the girdle at the sides to lace over the hips, although it is obvious that it may be separated or divided at any point or points around the body according to circumstances. The front half 1 of the girdle shown in the drawings is formed of any suitable material, but preferably of some non-elastic woven fabric and, as shown, is bound along its upper and

lower edges 4 and 5 with tape to provide strength and prevent wear. At one or more points along the front half 1 are provided substantially vertical reinforcing or strengthening straps 6, these being each preferably formed of non-elastic fabric and stitched or otherwise secured to the body or material of the girdle, preferably in such manner as to form between each strap 6 and the material of the girdle, one or more pockets 7, to receive stays 8, of any preferred form, to stiffen the girdle and cause the same to retain its form. At the ends 9 of the front half of the girdle, strips 10 of tape or other non-elastic material are provided, these being stitched or otherwise secured to the body 70 of the girdle and each provided with a pocket or pockets 11, preferably having a stay 8 therein, for the same purpose as those before mentioned, and an end portion 12 to receive the eyelets 3 for fastening the halves 75 of the girdle together.

The rear section of the girdle is in general of the same construction and arrangement as the front section, being bound at its upper and lower edges 13 and 14 with tape or other non-elastic fabric for strengthening the edges of the girdle. Vertical reinforcing strips 15 are provided at one or more points along the length of the rear half of the girdle, and these are preferably stitched or otherwise secured to the same in such manner as to provide pockets 16 for holding stays or other stiffening means. End strips 17 are also stitched or otherwise secured to the rear half of the girdle having pockets 18 therein for holding strengthening stays and having portions 19 through or in which are fastened the eyelets 3^a for fastening the rear half of the girdle to the front portion thereof.

The rear half of the girdle is approximately the same width throughout its length, but the proportions of the same will, of course, be varied in accordance with the requirements of the individual wearer thereof. The front half of the girdle is considerably wider near its center than at the sides and curves upwardly along its upper edge 4 and is provided with a downwardly projecting central portion or tab 21 along its bottom edge. The lower half of the girdle, including the downwardly projecting portion or tab 21 is drawn inwardly in use and tightly hugs and supports the lower portion

of the abdomen, the stays 8 and pockets 7 extending downwardly through the tab 21 to the lower edge thereof to stiffen it.

At suitable points above the lower edge of 5 the front half of the girdle 1 and preferably at about the middle horizontal line thereof I secure one or more garter attachments or supports 22, two such supports being shown in the drawings. These are each formed of 10 a strong band of any preferred nonelastic material or fabric, stitched or otherwise secured at its upper end to the body of the girdle. As shown, the supports 22 are arranged one on each side of the front strap 15 6^a, within the pockets of which may be provided stiffening stays 8 as before.

In use of the girdle, it is placed about the body of the wearer and the lacing ties 24 are drawn up tightly so that the girdle 20 forms to and assumes the shape of the body. As shown in Fig. 1, the lower portion of the front section of the girdle curves downwardly and inwardly in a vertical plane away from the garter supports and therefore 25 lies beneath the abdomen and supports the same. The garter supports 22 are attached at their upper ends only, to the girdle at the points 30, opposite the most protuberant portion of the abdomen, which, when the 30 girdle is in place, is considerably above the lower portion of the girdle and usually about midway between its upper and lower edges. The strain on the garter supports therefore not only prevents the girdle from 35 slipping upwardly on the body but, in fact, draws it downwardly and inwardly thereon, thus both reducing the protuberance and assisting in holding the lower portion of the girdle beneath the abdomen to support 40 the same. The girdle is very effective in

both sitting and standing positions of the wearer. When sitting, with the garters relaxed, the abdomen is both reduced and supported, the lacing ties 24 being drawn up sufficiently tight for this purpose. When 45 standing, the garter supports 22 not only form a means of attachment for the garters but also promote reduction and support of the abdomen and prevent slipping of the 50 girdle on the body.

The girdle may of course be used in surgical cases as a support or bandage for use after abdominal operations or, in cases of obesity, to reduce a protuberant abdomen.

What I claim is:—

An abdominal girdle or support comprising a front portion and a rear portion provided with means for drawing them tightly around the body of the wearer, the front portion being shaped to fit and cover the 60 abdomen only from substantially the waist line down, and a pair of depending garter supports secured at their upper ends only to said front portion substantially midway between the upper and lower edges thereof 65 and, when the girdle is in place on the body, opposite the protuberant portion of the abdomen, the lower part of the front portion of the girdle curving downwardly and inwardly beneath the lower portion of the 70 abdomen and being adapted to support the same irrespective of strain upon said garter supports.

In testimony whereof, I have hereunto set my hand.

EVA MAYNARD MARTIN.
